UNITED STATES PATENT OFFICE.

CHARLES T. REDFIELD, OF GLEN HAVEN, NEW YORK.

DESIGN FOR A THILL-CO尤PLING PLATE.

SPECIFICATION forming part of Design No. 26,584, dated February 2, 1897.

Application filed December 26, 1896. Serial No. 617,105. Term of patent 7 years.

To all whom it may concern:

Be it known that I, CHARLES T. REDFIELD, a citizen of the United States, residing at Glen Haven, in the county of Cayuga and State of New York, have invented and produced a new and original Design for Thill-Coupling Plates, of which the following is a specification, reference being had to the accompanying drawings, showing the same, in which—

Figure 1 is a perspective view, and Fig. 2 an edge view, of a thill-coupling plate embodying my design.

The leading feature of my design consists of a main portion bowed at the middle, having at one end a wing projecting at an angle and provided at its free edge with a flange, and the opposite end wing projecting in the

same general direction as the first-named wing, but made somewhat shorter than the same.

The main portion A is bowed at *a* and has the wings B and C projecting from it, the wing B being at an angle to the part A less than a right angle and having the flange *b*, and the edges of the wing C and flange *b* being notched, respectively, at *C'* and *b'*, as clearly shown.

What I claim is—

The design for a thill-coupling plate herein shown and described.

CHARLES T. REDFIELD.
